Primary Examiner—Robert M. Spear*Assistant Examiner*—Katrina A Kile(74) *Attorney, Agent, or Firm*—Knobbe, Martens, Olson & Bear LLP(57) **CLAIM**

The ornamental design for a vehicle storage rack, as shown and described.

DESCRIPTION

FIG. 1 is a perspective view of a storage rack showing my new design in accordance with a first embodiment of the invention;

FIG. 2 is a front elevational view of the vehicle storage rack of FIG. 1;

FIG. 3 is a rear elevational view of the vehicle storage rack of FIG. 1;

FIG. 4 is a bottom plan view of the vehicle storage rack of FIG. 1;

FIG. 5 is a top plan view of the vehicle storage rack of FIG. 1;

FIG. 6 is a left side elevational view of the vehicle storage rack of FIG. 1; and,

FIG. 7 is a right side elevational view of the vehicle storage rack of FIG. 1.
